UNITED STATES PATENT OFFICE.

RONALD A. McCANN, OF SWISSVALE, AND FRANK H. NICHOLSON, OF PHILADELPHIA, PENNSYLVANIA, ASSIGNEES TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed July 26, 1924. Serial No. 728,479.

To all whom it may concern:

Be it known that we, RONALD A. McCANN and FRANK H. NICHOLSON, citizens of the United States, residing, respectively, at 5 Swissvale, in the county of Allegheny and State of Pennsylvania, and at Philadelphia, in the county of Philadelphia and State of Pennsylvania, have invented certain new and useful Improvements in Railway-Traffic-10 Controlling Apparatus, of which the following is a specification.

Our invention relates to railway traffic controlling systems, and particularly to systems of the type wherein alternating currents are supplied to the track rails, and the cars or trains are provided with governing apparatus which is controlled by such currents in the rails. More particularly, 15 our invention relates to trackway circuits and apparatus for use in systems of the character set forth.

In one system of the type mentioned, it has been proposed to employ the usual track circuit current, that is, the current which energizes the track relays, as one of the currents for controlling the train-carried apparatus, and to supply another current (which we will term the "line current") to the rails of each track section in such manner that it flows in 20 the same direction in the two rails. When this is done, it will be seen that when a track section is occupied by a train, if the line current is of sufficient magnitude and of proper phase, and if it is sufficiently unbalanced in 25 the two track rails in the rear of the train, it may cause the track relay for such section to become energized, thus causing a false proceed signal in the rear of the train.

One object of our invention is the provision 30 of means for immediately opening the circuit for the line current for a track section in the event that such current causes energization of the track relay when the section is occupied, thus preventing a false proceed signal in the rear of the train. This 35 will cause the train to be stopped or to be brought down to a predetermined low speed, but the train will be protected by a stop signal.

50 We will describe several forms of trackway circuits and apparatus embodying our invention, and will then point out the novel features thereof in claims.

In the accompanying drawings, Fig. 1 is a

diagrammatic view showing one form of 55 trackway circuits and apparatus embodying our invention. Figs. 2, 3 and 4 are views similar to Fig. 1 but showing modifications of the circuits and apparatus illustrated 60 therein.

Similar reference characters refer to similar parts in each of the views.

Referring first to Fig. 1, the reference characters 2, 2^a designate the two track rails of a railway along which traffic normally moves in the direction indicated by the arrow. The rails are divided, by insulated joints 3, into a plurality of sections or blocks, of which one complete section C—D is shown in the drawing, except that the apparatus of section C—D the sole functions of which is to control traffic signals and indications in the section to the left of point C are omitted to simplify the drawing, they not being necessary for a full understanding of the 75 invention described herein. It is understood, however, that a complete system embodying our invention will usually comprise a plurality of successive sections each of which is equipped with apparatus similar to that shown for section C—D.

Located adjacent the entrance end of section C—D is a roadside signal S^c of the semaphore type, which signal indicates "stop", "caution" or "proceed" according as 80 the semaphore is in the horizontal, inclined or vertical position. A similar signal S^d is provided for the section immediately to the right of section C—D.

The section C—D is provided with a track 90 circuit comprising a source of alternating current (transformer T) and a winding 4 of a polyphase relay H, the source and the relay winding being connected across the track rails at the exit and entrance ends 95 of the section, respectively. Relay H comprises the winding 4, which we will term the "track winding", a second or "local winding" 5, a rotor 6 responsive to currents displaced in phase in the two windings, and two contacts 7 and 8 operated by the rotor. The local winding 5 is supplied with alternating current of the same frequency as that supplied to the primary of transformer T, but displaced in phase from the current in winding 4 by substantially 90°. The transformer T is connected with the rails through 100 a reactance 70, and the polarity of the cur-

rent supplied by this transformer is controlled by a pole-changer P actuated by signal S^D . When this signal is in the proceed or caution position, pole-changer P is in such position as to supply current of what we will term normal polarity to the track rails, in which case the contacts of relay H are swung to the right as shown; but when signal S^D is in the stop position, pole-changer P is reversed so that current of reverse polarity is supplied to the track rails, in which case the contacts of relay H are swung to the left. Of course, when track section C—D is occupied by a car or train, the supply of track circuit current from transformer T to the track winding 4 of relay H is discontinued, so that this relay becomes de-energized and contacts 7 and 8 move to the vertical position.

Signal S^c is provided with a caution circuit and a proceed circuit, which circuits are controlled by contact 7 of the track relay H and by the front point of a contact 10 of a slow-releasing stick relay E. The caution circuit for signal S^c is from one terminal B of a suitable source of current through front point of contact 10 of relay E, wires 14, 15 and 16, left-hand point of contact 7 of track relay H, wire 18 and operating mechanism of signal S^c to the other terminal O of the same source of current. It will be seen that this circuit is closed only when relay E is energized and relay H is energized by track circuit current of reverse polarity. The proceed circuit for signal S^c is from terminal B through the front point of contact 10, wires 14, 15 and 16, right-hand point of contact 7, wire 17, and mechanism of signal S^c to terminal O. It will be seen that this circuit is closed only when relay H is energized by track circuit current of normal polarity and relay E is energized.

The stick relay E is provided with a pick-up circuit which is controlled by contact 8 of relay H and by a contact 13 actuated by signal S^c and closed only when the signal indicates stop. This circuit is from terminal B' of a suitable source of current, through contact 13, wires 19 and 20, right or left-hand point of contact 8, wire 21 or wire 15, wire 14, back point of contact 10 of relay E, wires 22 and 23, and the winding of relay E to the other terminal O' of the same source of current. It will be seen that this circuit is closed only when signal S^c is in the stop position, relay H is energized, and the back points of relay E are closed. Relay E is provided with a stick circuit which passes from terminal B, through the front point of contact 10, wire 14, wire 21 or wire 15, right or left-hand point of contact 8, wire 20, contact 9, wire 23, and winding of relay E to the

other terminal O' of the source of current. This stick circuit, it will be noted, is closed only when relays E and H are both energized.

The operation of the apparatus, in so far as the control of signal S^c is concerned, is as follow:

When the track section C—D is unoccupied, and signal S^D is in the proceed or caution position, relays H and E are both energized, relay H being energized in the normal direction, so that signal S^c indicates proceed. If then a car or train enters section C—D, it causes relay H to become de-energized, thereby opening the stick circuit for relay E at contact 8 and also opening the control circuits for signal S^c at contact 7, so that relay E opens and the signal moves to the stop position.

It will be noted that the opening of relay E opens at contact 10 the control circuits for signal S^c , and it will also be noted that relay E cannot again become energized until signal S^c has reached the stop position. It follows, therefore, that if track relay H should wrongly become energized while signal S^c is moving toward the stop position, the signal will, nevertheless, complete its movement to this position. The reason for this control of signal S^c by contact 10 will be pointed out hereinafter.

As soon as the entire car or train has passed out of section C—D, track relay H becomes energized in the reverse direction, thereby closing at contact 8 the pick-up circuit for relay E. As soon as this relay becomes energized, the stick circuit hereinbefore traced for this relay becomes effective to hold the relay E in the energized condition as long as track relay H continues to be energized. The caution circuit for signal S^c is then closed, so that the signal moves to the caution position. When the entire car or train has passed out of the section to the right of section C—D, the polarity of the track circuit current in section C—D becomes normal, whereupon signal S^c moves to the proceed position.

Relay E is preferably slow-releasing in character, in order to avoid de-energization of this relay while contact 8 of relay H is swinging from the right to the left-hand position, or vice-versa, due to change of polarity when pole-changer P reverses.

The trackway apparatus shown herein includes means for causing an alternating line current to flow along the two track rails of the section C—D in the same direction, which current is controlled by traffic conditions in advance. This current is supplied by a transformer U. When signal S^D is in the proceed or caution position, the path of the line current is from transformer U, through wire 24, contact 25 operated by signal S^D , wire 26, to the middle point of an

impedance 27, thence through the two track rails 2 and 2^a in multiple to a second impedance 28 from the middle point of which the current flows through wires 29 and 33, 5 back contact 11 of relay E, and wires 34 and 32 to transformer U. When signal S^D is in the stop position, wire 24 is disconnected from wire 26 and connected with a wire 35 which leads to the middle point of an impedance 36, so that the line current is then supplied to the track rails only between impedances 36 and 28.

It will be seen, then, that one or the other of the circuits just traced will be closed 15 when a train enters section C—D, provided that track relay H opens. In the event that this relay should stick in the closed position due to a mechanical defect, however, it is desirable that line current be supplied to 20 the rails to avoid stopping the train; to do this, we provide the circuit for the line current with a branch around relay contact 11, which branch is from wire 29, through wire 30, signal operated contact 12 and wire 31 to 25 wire 32. Contact 12 is closed when signal S^c indicates proceed and caution, but open when the signal indicates stop. By virtue of this branch, then, the line circuit is closed when signal S^c is in the proceed or caution 30 position, even though relay contact 11 may be open.

Before proceeding further, it should be pointed out that the trackway apparatus here shown is intended for co-operation with 35 train-carried governing apparatus in the following manner: When the train is on a portion of track which is supplied with track circuit current of normal polarity and also with line current, the governing apparatus 40 permits the train to travel at high speed, such as 60 miles per hour. When the track is supplied with line current and the track circuit current of reverse polarity, the governing apparatus prevents the train from 45 proceeding at more than an intermediate speed, such as 35 miles per hour, but when the train enters a portion of track from which the supply of either track circuit current or line current has been discontinued, 50 the governing apparatus prevents the train from proceeding at more than a low speed, such as 10 miles per hour. One form of governing apparatus which will co-operate in this manner with the trackway apparatus 55 shown herein is illustrated and described in Letters Patent of the United States No. 1,351,991 granted on the 7th day of September, 1920, to Lloyd V. Lewis, for railway traffic controlling systems.

60 Assuming now that a car or train has entered section C—D, it will be remembered that the de-energization of track relay H causes stick relay E to open. The closing of the back contact 11 of relay E closes the 65 circuit for the line current, so that the open-

ing of contact 12 due to the movement of signal S^c to stop has no effect on the supply of this current to the rails of the section.

Assuming now that section C—D is occupied by a car or train, it is conceivable 70 that owing to a difference in the resistances of the two lines of track rails the line current in the rear of the train may be sufficiently unbalanced in the two rails to cause track relay H to become energized. If this 75 happens, the closing of contact 8 will close the pick-up circuit for relay E, whereupon this relay will become energized. Contact 11 then opens, so that the supply of line current to the rails of section C—D is immediately discontinued. Track relay H will, 80 therefore, again become de-energized, but relay E will remain energized owing to an auxiliary stick circuit which passes from terminal B' through contact 13, wire 19, 85 contact 9, wire 23 and winding of relay E, to terminal O'. The result is that signal S^c will remain in the stop position, because its controlling circuits are opened at contact 7 of relay H, and relay E will remain energized. Contacts 11 and 12 then both being 90 open, the supply of line current to the rails of section C—D is discontinued, and the car or train which is in section C—D is, therefore, deprived of line current, so that 95 its progress through the remainder of this section is limited to a speed not exceeding 10 miles per hour. This car or train is, however, protected by a stop signal in its rear. As soon as the entire car or train 100 passes out of section C—D, track circuit current is again supplied to winding 4 of relay H, so that this relay becomes energized and so causes signal S^c to move to the caution position. The stick circuit for 105 relay E which includes contact 13, becomes opened as soon as the signal leaves the stop position, but the main stick circuit for this relay is then closed at contact 8, so that relay E continues to be energized. When the 110 signal S^c reaches the caution position, the line circuit for section C—D becomes closed at contact 12, so that line current is again supplied to the rails of section C—D.

One important feature of our invention 115 is that the circuit for the line current is normally closed when section C—D is unoccupied and signal S^c is at proceed or caution, but that this circuit is opened and remains open in the event that track relay H 120 becomes energized by line current while the section is occupied by a car or train.

Another feature of the invention is that in the event of sufficient unbalancing of the 125 line current to energize the track relay in the rear of a train, the abnormal condition is detected by the reduction in the speed limit of the train.

It should be observed that when a train 130 enters section C—D, the track relay H will

be de-energized regardless of unbalancing of the line current in the track rails, because the train then forms a shunt directly across the terminals of winding 4 of this relay.

5 If the pick-up circuit for relay E were controlled only by track relay contact 8, it is possible that when a locomotive or a short train enters the section C—D at high speed, track relay winding 4 might become sufficiently energized by unbalanced line current to cause the contacts of the track relay to close before signal S^c gets beyond the caution position. Relays H and E would then both be closed, so that signal S^c would remain in the caution position or would return to the proceed position, and the track relay would continue to be energized due to the flow of line current through contact 12, so that the object of our invention would be defeated. To avoid such a condition, the pick-up circuit for relay E includes contact 13, so that when relay E has once been opened, due to the entrance of a car or train upon section C—D, it cannot again become closed until signal S^c has reached the stop position. Contact 12 is then open, so that as soon as relay E picks up, the circuit for the line current becomes opened at contact 11 and thereafter remains opened until track relay winding 4 becomes energized by track circuit current.

10 The apparatus and circuits shown in Fig. 1 are suitable for use in connection with roadside signals of the "direct connected" type, that is, the type wherein the semaphore and the operating motor are constantly connected by gearing. The arrangement shown in Fig. 1 may not be suitable, however, for use with signals of the "slot arm" type, that is, signals in which a magnet-controlled clutch is employed to connect the motor and the semaphore and to hold the semaphore in the caution and proceed positions. The reason for this is that if a slot arm type of signal were controlled by the circuits shown in Fig. 1, reversal of the track relay while the signal is at caution or proceed, would momentarily de-energize the clutch magnet and so might permit the semaphore to drop to the stop position. The arrangement shown in Fig. 2 is adapted for use in connection with signals of the slot arm type.

15 Referring now to Fig. 2, the apparatus and circuits shown therein are the same as those shown in Fig. 1, except for the circuits which control signal S^c . The caution circuit for signal S^c is from one terminal B^2 of a source of current, through contact 37 of relay H, wires 40 and 41, contact 38 of relay E, wires 43 and 18, and mechanism of signal S^c to the terminal O of the source of current. The proceed circuit is likewise through contacts 37 and 38, wire 43, thence through wire 39, contact 7 of relay H, wire

17, and the operating mechanism of signal S^c to the terminal O. Each of these circuits is provided with a branch around track relay contact 37, which branch passes from terminal B' of the source of current, through signal operated contact 13, and wire 42 to wire 41. This branch is, of course, closed only when the signal is in the caution or proceed position, and is opened when the signal is at stop. 75

The operation of the apparatus shown in Fig. 2 is so nearly like the operation of that shown in Fig. 1 that no further explanation is required. It will be observed that when the signal is in the caution position, reversal of the track relay will not cause the caution circuit for the signal to be momentarily opened because this circuit will be closed by virtue of the branch including contact 13. The signal will, therefore, not move to the stop position during such reversal, as might be the case were a slot arm type of signal used with the circuits shown in Fig. 1. 80

10 It is obvious that the apparatus and circuits shown in Figs. 1 and 2 cannot be employed in connection with roadside signals of the "light" type, that is, signals comprising electric lamps only, because such signals have no moving parts which can be utilized to operate the contacts 12, 13 and 25. When signals of this type are used, the apparatus shown in Fig. 3 may be employed. 95

100 Referring now to Fig. 3, each signal S in the form here shown comprises three electric lamps R, Y and G, which lamps, when illuminated, indicate respectively "stop", "caution" and "proceed". The track circuit shown in this view is the same as that shown in Fig. 1, except that the polarity of the track circuit current is controlled by a pole-changing relay K, which relay in turn is controlled by a contact 44 of track relay H^P . When track relay H^P is energized in either normal or reverse direction, relay K is energized, and current of normal polarity is then supplied to the track circuit of sections C—D; but when track relay H^P is de-energized, relay K is likewise de-energized and current of reverse polarity is then supplied to the track circuit of section C—D. The circuit for the line current for transformer U is the same as the corresponding circuit in Fig. 1 except that the supply of this current to impedance 27 or impedance 36 is controlled by contact 25^a of a relay L, which relay in turn is controlled by a contact 45 of track relay H^P . When track relay H^P is energized in either normal or reverse direction, relay L is energized, and line current is then supplied to the rails of section C—D throughout the entire length of this section; but when relay H^P is de-energized relay L is likewise de-energized so that line current is supplied to the rails of section C—D between impedance 28 and 36 only. 110

115 120 125 130

The branch around relay contact 11 in the line circuit is controlled by a contact 55 of a slow-acting relay J, which relay is controlled in the manner hereinafter explained. 5 Relay J is so constructed that it is slow-releasing and also slow-pick-up.

The lamps of signal S^c are controlled by relay H and by relay E. The circuit for the proceed lamp G is from terminal B of a 10 source of current through the front point of contact 38 of relay E, wires 46 and 47, right-hand point of contact 7 of relay H, wire 17 and lamp G to terminal O of the same source of current. The 15 circuit for the caution lamp Y is through the front point of contact 38, the left-hand point of contact 7, and wire 18 to lamp Y. The circuit for the stop lamp R is from terminal B through the back point 20 of contact 38 of relay E, wires 48 and 56, and lamp R to terminal O.

While the section C—D is unoccupied, relay E is energized by virtue of its normal stick circuit, which is from terminal B' of 25 a source of current through the front point of contact 10 of relay E, wire 14, contact 37, wire 50, contact 9, wire 23, and winding of relay E to terminal O' of the same source of current. Relay J is also energized at such 30 times, the circuit being from terminal B through the front point of contact 38 of relay E, wires 46 and 53, contact 8 of relay H, wire 54, and winding of relay J to terminal O² of the same source of current.

We will now assume that a car or train 35 enters section C—D, thereby de-energizing track relay H. The opening of contact 37 opens the stick circuit for relay E so that this relay becomes de-energized, thereby 40 causing stop lamp R to become illuminated. The opening of contacts 8 and 38 likewise cause relay J to become de-energized. When such train passes out of section C—D, the energization of relay H causes the pick-up circuit 45 of relay E to become closed, this circuit being from terminal B² of a source of current, through contact 52 of relay J, wires 51 and 50, contact 37 of relay H, wire 14, back point of contact 10 of relay E, wires 50 52 and 23, and winding of relay E to terminal O' of the source of current. Relay E is then held closed by its stick circuit herein before traced, and after a certain interval of time relay J operates to open its back contacts and close its front contact.

We will now assume that while the section C—D is occupied by a car or train, the unbalancing of the line current in the rails in the rear of such car or train is sufficient 55 to energize relay H. The pick-up circuit for relay E is then closed at contacts 52 and 37, and as soon as this relay becomes energized and auxiliary stick circuit is closed, which circuit passes from terminal B² through back

contact 52 of relay J, wire 51, contact 9 of relay E, wire 23, and winding of relay E to the terminal O' of the source of current. The energization of relay E opens contact 11 and since contact 55 is open, this cuts off the supply of line current to the track rails so that relay H opens, but relay E remains energized due to the stick circuit just traced. At such time the normal circuit for the stop lamp R of signal S^c is open at the back point of contact 38 of relay E, but an auxiliary circuit 70 for this lamp is closed which passes from terminal B³ through back contact 71 of relay J, wires 72 and 56, and lamp R to terminal O. The time required for relay J to 75 pick-up is greater than the time required for relay H to open after relay E closes, and so relay J remains de-energized during the improper operation of track relay H just referred to.

The function of relay J in Fig. 3 is to provide a time element corresponding to the time required for the semaphore signals in the preceding views to operate. This relay must be open to permit relay E to close, and after E closes, the track relay H must remain closed for a certain time interval before relay J will close. But if the track relay is falsely closed by line current it is apparent that the supply of such current will 85 be cut off by the closing of relay E and the track relay will open before relay J can 90 close. Both contacts 11 and 55 will then remain open until the car or train leaves section C—D.

Referring now to Fig. 4, the track circuit 100 and the circuit for the line current are the same as in Fig. 1, but the local circuits for the control of relay E, and the manner in which this relay controls the supply of line current to the rails, are somewhat different. In Fig. 4 the circuit for the local winding 105 5 for the track relay H is controlled by contact 10 of relay E. When relay E is energized, this winding is supplied with current from terminal B' of a suitable source, through the front point of contact 10, wire 60, and winding 5 to terminal O'. When relay E is de-energized, winding 5 is supplied with current, provided that signal S^c is in 110 the stop position, the circuit then being from terminal B² through contact 13, wire 59, back point of contact 10, wire 60 and winding 5 to terminal O'. Relay E is provided with a pick-up circuit which is controlled only by contact 8 of relay H, the circuit being from terminal B³ through contact 8, wires 57 and 58, and relay E to terminal O³. Relay E is also provided with a stick circuit, which is as follows: from terminal B² through contact 13, wire 59, contact 9, 115 wires 61 and 58, and winding of relay E to terminal O³.

In Fig. 4, signal S^c is controlled only by

contact 7 of relay H. The caution circuit for this signal is from terminal B through the left-hand point of contact 7, wire 18, and mechanism of signal S^c to terminal O. The proceed circuit is from terminal B through the right-hand point of contact 7, wire 17 and mechanism of signal S^c to terminal O.

When a car or train enters section C—D, it, of course, causes track relay H to open due to de-energization of winding 4. This causes signal S^c to move to the stop position, and it also opens the pick-up circuit for relay E, which relay, therefore, becomes de-energized. As soon as S^c reaches the stop position, the auxiliary circuit for the supply of current to winding 5 is closed at contacts 13 and back point of contact 10. If, while section C—D is occupied, relay H should become energized, due to unbalancing of the line current in the rear of the train, relay E will close, whereupon its stick circuit will be closed through contacts 13 and 9. The opening of contact 11, however, will immediately discontinue the supply of line current to the rails, so that track relay H will again open. Signal S^c will, consequently, remain at stop, so that relay E will remain energized. As soon as the car or train passes out of section C—D, relay H will be-
come energized, so that signal S^c will move to the caution or proceed position, whereupon the parts will again occupy the positions in which they are shown in Fig. 4. Relay E is slow-acting in order that a quick reversal of relay H will not open relay E and thereby disconnect energy from winding 5 of relay H.

In each of the views the source or sources of current have been omitted to simplify the drawing, and the two terminals of each source are represented by the letters B and O respectively, exponents being applied to these letters in some instances to facilitate the tracing of the several circuits. It is understood, however, that in each view the terminals B, B', etc. may, if desired, be one and the same terminal of a single source of current, the same thing being true as to the terminals O, O', etc. In other words, in actual practice only one source of current will usually be provided at each signal location, the points B, B', etc. being connected with one terminal of such source, and the points O, O', etc. being connected with the other terminal.

The present application is for the same invention as an earlier application filed by us on the 23rd day of April, 1919, Serial No. 292062, for railway traffic.

Although we have herein shown and described only a few forms of trackway apparatus and circuits embodying our invention, it is understood that various changes and modifications may be made therein within the scope of the appended claims

without departing from the spirit and scope of our invention.

Having thus described our invention, what we claim is:

1. In combination, a section of railway track, a track circuit comprising a source of current and a track relay both of which are connected across the rails of said section, a stick relay, a roadside signal controlled by said track relay and by said stick relay, a line circuit including the two rails of said section in multiple, said latter circuit having two branches one of which is closed or open according as said signal indicates proceed or stop and the other of which is closed or open according as said stick relay is de-energized or energized, a pick-up circuit for said stick relay including a track relay contact closed only when the track relay is energized and a signal operated contact closed only when the signal is at stop, a holding circuit for said stick relay including a front contact of the stick relay and a signal operated contact closed only when the signal is at stop, and a second holding circuit for said stick relay including a front contact of the stick relay and a track relay contact closed only when the track relay is energized.

2. In combination, a section of railway track, a track circuit comprising a source of current and a track relay both of which are connected across the rails of said section, a stick relay, a roadside signal controlled by said track relay and by said stick relay, a line circuit including the two rails of said section in multiple, said latter circuit having two branches one of which is closed or open according as said signal indicates proceed or stop and the other of which is closed or open according as said stick relay is de-energized or energized, means for energizing said stick relay when the signal is at stop and the track relay is energized, and means for subsequently keeping said stick relay energized while the signal is at stop even though the track relay becomes de-energized.

3. In combination, a section of railway track, a track circuit comprising a source of current and a track relay both of which are connected across the rails of said section, a stick relay, a roadside signal controlled by said track relay and by said stick relay, a line circuit including the two rails of said section in multiple, said latter circuit having two branches one of which is closed or open according as said signal indicates proceed or stop and the other of which is closed or opened according as said stick relay is de-energized or energized, means for energizing said stick relay when the signal is at stop and the track relay is energized, and means for subsequently keeping said stick relay energized while the signal is at stop even though the track relay becomes de-energized.

de-energized, and while the track relay is energized even though the signal moves away from the stop position.

4. In combination, a section of railway track, a track circuit including a source of current and a track relay both of which are connected across the rails of the section, a signal for the section controlled by said track relay, a line circuit including the two rails of said section in multiple, said latter circuit also including two branches in multiple one of which is open or closed according as said signal indicates stop or proceed, and means for opening the other of said branches when the signal is at stop and the track relay is energized and for keeping said latter branch open if the track relay subsequently becomes de-energized, said means also operating to require that the signal make a complete movement to stop position when the track relay becomes de-energized even though the track relay again becomes energized before such movement is completed.
5. In combination, a section of railway track provided with a track relay, a line circuit for said section, and means operating if said relay becomes closed by line circuit current when the section is occupied to open the

line circuit and keep it open until the section becomes unoccupied.

30

6. In combination, a section of railway track provided with a track relay, a line circuit for said section including the track rails of the section in multiple, and means operating if said relay becomes closed by line circuit current when the section is occupied to open the line circuit and keep it open until the section becomes unoccupied.

35

7. In combination, a section of railway track provided with a track relay, a line circuit for said section, a signal controlled by said track relay, and means operating if said relay becomes energized by line current while the signal indicates stop to open said line circuit and keep it open until the signal again gives a proceed indication.

40

8. In combination, a section of railway track provided with a track relay, a line circuit for said section, and means for effecting a constant opening of said line circuit if said track relay becomes falsely energized by line circuit current.
